UNITED STATES PATENT OFFICE.

R. A. NATHURST AND J. L. STEWART, OF NASHVILLE, TENNESSEE.

SAFETY-REIN FOR BRIDLES.

Specification of Letters Patent No. 25,135, dated August 16, 1859.

To all whom it may concern:

Be it known that we, RUDOLPH A. NAT-
HURST and JOHN L. STEWART, both of Nash-
ville, in the county of Davidson, in the State
5 of Tennessee, have invented a new and
highly useful Improvement which we call
a "Safety-Rein," being an attachment to
the bridle or halter of a horse or of any
similarly geared animals, and which appli-
10 cation will give the driver a complete con-
trol over his beast, particularly in stopping
a frightened or starting a balky animal;
and we do hereby declare that the following
15 is a full and exact description thereof, ref-
erence being had to the accompanying draw-
ings and to the letters of reference marked
thereon.

To enable others to understand, construct
and make use of our invention we will pro-
20 ceed to describe its nature construction and
operation.

The nature of our invention and its pec-
uliarity consist in the providing of an
extra strop, lettered A on the accompanying
25 drawings, which connects with the common
driving-rein C and C_c, at a convenient dis-
tance from the animal's head, and after
passing through a ring (R), a loop or pulley
30 may be substituted, it passes under the ani-
mal's neck, either in form of a plain, flat
or round strop or widened and stuffed into
a pad, as shown and lettered P on the
drawing, and continues exactly alike on the
35 other side, passing up through another ring
(like R) and connects there with the other
line of the driving-rein. These rings, (of
which R represents one) are held up by the
broad strop F across the back of the ani-
40 mal's neck, as illustrated by the drawing,
and it is almost needless to state that these
drawings represent a part of a horse, viz:
Head, neck and shoulder, with a bridle and
safety-rein attached. And as one side com-
45 pletely shows how the other does look, we
have deemed it useless to furnish but one
representation, hoping that it will be so
considered by all whom it may concern.

The strop A has a buckle b, by which its
50 length can be properly regulated.

The punctuation on the drawings marked
d is intended to show the mode in which the
above named rings should be secured to the
bridle when made in one with it. The
55 buckle-strops (S) secures these same rings
to the bridle and prevent the sliding back
of the noose formed by the strops F and A

and the rings, which also can be perma-
nently affixed alike on both sides of the
animal's head.

The section or sections of the common 60
driving-reins reaching from the bridle or
halter (as the case may be) and to the con-
junction of the strop A and is marked C_c
have on each side an elastic section (e) made
of a spiral-spring, gutta percha, india rub- 65
ber or any other suitable substance. But to
make the action and effect of our safety-
rein easily understood, we will go into a
still more explanatory description of our
invention and its use. Suppose, therefore, 70
that we wish to turn our horse to the right
and for that purpose pull at the right hand
line of the reins—it will be evident that its
action on the bit is just the same as usual,
because the strop A pulls through the ring 75
(R), upwards on the right side and down-
wards on the left side, thereby obviating
any choking or action on the throat. The
same thing takes place in an opposite way
when the left hand line of the reins are 80
pulled. Again, if both the right and left
lines of the reins are drawn in simultaneous,
the effect will also, if the pull is gentle or
slight, be the usual drawing in of the bit, but
if this has not the desired effect of checking 85
the horse and a harder pull is resorted to,
the animal's head will be drawn in toward
the chest, the elastic sections will elongate
and the main force of the pull will conse-
quently take effect on the choking-attach- 90
ment, that is: the strop A will run upwards
through the rings (R) on each side and
press forcibly on the wind-pipe and thus
by taking the animal's breath away, it is
most certain to bring it to a sudden stand- 95
still—because no animal whose breath is
taken away can run but a few steps. The
reins are no sooner let loose or eased before
this effect ceases, and the animal is never
hurt by this as by many of the cruel bits 100
that are in use to this day. Again, when a
horse or other animal in reins, has the bad
habit of balking, a quick and strong pull
with the described sudden choking action,
confuses and startle the horse and thereby 105
makes him run forwards which is the ob-
ject, and after a few times applications, will
invariably cure it from this most annoying
and dangerous habit.

Our belief is, that horses and other ani- 110
mals broke to work or riding with this
safety-rein from the beginning, will be rode

or drove more safely even without the use of the bit, than now is the case, or in the usual way with any kind of a bit. And we think that when this safety rein is fully introduced the bit will if not entirely go out of use, it will at least only exist in its most innocent form.

We do not claim a mere choking-strop with its separate reins, for this we understand 10 has been used before, neither do we claim a connection of choke-pads over the horse's nostrils with the bit, as patented by William D. Titus & Co 1855, but

We claim

The connection of the choke-strop with 15 the common or ordinary driving rein, so as to act and serve for both purposes of driving and safety-rein substantially as described, and this we claim whether it be temporary or permanently affixed to the 20 bridle or halter, whether a bit is used or not.

RUDOLPH A. NATHURST.

JOHN L. STEWART.
